UNITED STATES PATENT OFFICE

PAUL JOZSY, OF NEW YORK, N. Y.

TONE CLARIFIER

Application filed April 1, 1931. Serial No. 526,959.

This invention relates to tone clarifiers for use with musical instruments, such for example as a radio receiving set, a phonograph, a band or orchestral instrument.

5 The device may be disposed outside of a musical instrument or in the sound emitting throat thereof, and the distance of the device of my invention from the instrument may be varied in order to vary the loudness of the 10 sound, the sound being louder the nearer the device is to the instrument.

An object of the invention is the provision of a tone clarifier of novel and efficient structure.

15 Other objects will be appreciated by those skilled in the art upon reading the following specification.

The invention will be fully and comprehensively understood from a consideration of the following detailed description when read in connection with the accompanying drawings which form part of the application, with the understanding, however, that the improvement is capable of extended application and 25 is not confined to the exact showing of the drawings nor to the precise construction described, and, therefore, such changes and modifications may be made therefrom as do not affect the spirit of the invention nor exceed the scope thereof as expressed in the appended claims.

In the drawings:

Fig. 1 is an elevational view of a phonograph partly broken away.

Fig. 2 is a plan view of the interior structure of one form of my invention, the casing therefor being partly in section and the cover for the casing being broken away.

Fig. 3 is a vertical section taken on line 3—3 of Fig. 2.

Fig. 4 is an elevational view of a radio receiving set or phonograph and an elevational view of the device of my invention set before the musical instrument.

Fig. 5 is a view similar to Fig. 2, showing another form of my invention.

Fig. 6 is a vertical section taken on line 6—6 of Fig. 5.

Fig. 7 is a perspective view of still an-

other form of my invention, the cover for the casing being broken away to show the interior structure.

Fig. 8 is a view similar to Figs. 2 and 5 and shows the form of invention depicted in Fig. 55 7; and

Fig. 9 is a vertical section taken on line 9—9 of Fig. 8.

Referring to the drawings for a more detailed description thereof, and at first to Figs. 2 and 3, in which one form of my invention is shown, the numeral 10 indicates a casing comprising a body portion 11 of generally rectangular form. The casing also comprises a bottom 12 secured to the body portion 11 by means of screws 13. A cover 14 is provided for the casing and secured to the body portion 11 by means of screws 15. The front part of the casing is provided with a screen 17 having a plurality of apertures 18 therein to allow sound from a musical instrument to enter the casing. The screen 17 is secured to the casing by being disposed in vertical slots 19 formed in the sides of the casing. The screen may additionally be soldered to the casing which is preferably of metal, although it may be of any other material. The rear wall 11a of the body portion 11 of the casing is provided with apertures 21 to allow sound to be emitted from the casing. The 70 number and size of the apertures 21 may be varied in accordance with the requirements, which vary with the type of instrument with which the device of my invention is used. The louder the sound emitted by a musical instrument the more will be the number of apertures 21 provided. A series of spaced parallel baffles 23 are secured to the bottom 12 of the casing 11 by means of brackets 25 which are secured to the baffles by means of rivets 26, and to the bottom 12 of the casing by means of rivets 26'. The baffles 23 are vertical and are disposed on their edges as shown.

The baffles 23 as shown in Figs. 2 and 3 extend at right angles to the front and the back of the casing and parallel with the sides thereof. Another series of parallel spaced plates, set on their edges, is provided, these plates being designated by the numeral 27 and be- 95 100

ing secured to the bottom 12 of the casing by means of brackets 29.

Brackets 29 are secured to the baffles 27 by means of rivets 30 and are secured to the bottom 12 of the casing by means of rivets 31. The baffles 27 are disposed at an angle to the baffles 23, respectively, each pair of baffles comprising a baffle 23 and a baffle 27 forming a V. The front ends of the baffles 23 and their corresponding baffles 27 are slightly spaced apart as shown at 33 in Fig. 2. The baffles 27 are preferably somewhat thicker than the baffles 23 as shown in Fig. 2. An end baffle 23 is preferably bent outwardly as shown at 23a in Fig. 2. Back of the baffles 23 and 27 is disposed a vertical foraminated plate 35 having apertures 36, the number of which apertures may be varied in accordance with the peculiarities of the instrument with which the tone clarifier is used, the louder the tones from the musical instrument the more apertures 36 there will be. This plate 35 assists the baffles 23 and 27 in producing tone clarification.

The louder the sound from a musical instrument the greater will be the angle at which the baffles 23 will be disposed relative to the baffles 27 and the baffles will be longer the louder the sound from the musical instrument.

Referring now to Figs. 5 and 6 showing a modification of my invention, the structure of the casing is similar to that described and shown in Figs. 2 and 3. However instead of providing the casing with apertures 21 as in Figs. 2 and 3, a screen 40 is provided in the back of the body portion 11 of the casing, this screen having apertures 41 and being disposed at an aperture 42 cut in the back of the casing. The screen 40 functions to allow sound to be emitted from the casing. A foraminated plate 35 having apertures 36 is provided in this form of the invention as in the form shown in Figs. 2 and 3. In this form of the invention vertical baffles 44 are secured on their edges by means of brackets 45 which are secured to the bottom 12 of the casing by means of rivets 46 and are secured to the baffles by means of rivets 47. The baffles 44 are so disposed toward each other that adjacent baffles form V's. The ends of adjacent baffles however do not quite contact with each other, providing spaces 49 as shown in Fig. 5. These spaces allow the sound to pass between the baffles.

Referring now to Figs. 7, 8 and 9, in which still another form of my invention is shown, the casing herein shown is the same as that shown in Figs. 2 and 3. A foraminated plate 35 having apertures 36 is provided in this form of the invention as it is provided in the two forms previously described. In this form of the invention baffles 51 form V's with baffles 52, spaces 53 being provided between the rear ends of the baffles 51 and 52 to allow

sound to pass. Baffles 54 and baffles 55 are disposed in V formation and reversely set with respect to baffles 51 and 52, the baffles 54 and 55 having spaces 57 between their forward ends to allow sound to pass therethrough. The baffles 51, 52, 54 and 55 are vertically disposed with their edges resting on the bottom 12 of the casing and are secured in place by means of brackets 59 secured to the bottom 12 of the casing by rivets 60 and 75 secured to the baffles by means of rivets 61.

Referring now to Fig. 4, the numeral 63 indicates a musical instrument such for example as a radio receiving set or a phonograph provided with a horn 64 before which 80 is set at any suitable distance a device 66 comprising a base 67 supporting a standard 68 on which rests a tone clarifier 69 of my invention, any one of the three forms previously described being used. Clarifier 69 is 85 provided with the sound gathering structure 70 secured to the front of the clarifier.

The structures hereinbefore described are capable of clarifying sounds for musical instruments so as to render the sounds very 90 pleasing to the ear, much more so than if my device were not used. It will be understood, since it is well known in the art, that the baffles hereinbefore mentioned are vibrated by sound.

What is claimed as new is:

1. A tone clarifier comprising a casing and baffles disposed transversely of the casing, alternate baffles being parallel and adjacent baffles arranged in V formation, the end of each baffle being in close proximity to the end of the next adjacent baffle.

2. A tone clarifier comprising a casing and baffles secured edgewise in the casing, said baffles being arranged in pairs, each pair being of V formation and adjacent pairs being oppositely positioned.

3. A tone clarifier comprising a casing and baffles secured edgewise in the casing, said baffles being arranged in pairs, each pair being of V formation and adjacent pairs being oppositely positioned, an end of each baffle being bent at an angle to the main portion of the baffle.

In testimony whereof I hereby affix my 115 signature.

PAUL JOZSY.
